COMBINATION CUTLERY TOOL

Harlow C. Platts, Boulder, Colo., assignor to The Western States Cutlery and Manufacturing Company, a corporation of Colorado

Application March 13, 1950, Serial No. 149,421

1 Claim. (Cl. 30—342)

This invention relates to a combination tool providing interchangeable hand ax and knife blades.

For a considerable number of years it has been generally recognized that a hand ax and some type of hunting knife were advisable items of equipment for those who engage in hunting or other similar outdoor activities. In recent years many different types of hunting knives have been devised to satisfy the demand for suitable instruments of this type. At the same time different types of construction for hand axes have been devised in an endeavor to develop an ax that would be thoroughly suited for its intended purposes. In general the main objects pursued in devising the various new types of hand axes and knives has been to reduce the total weight of the tools while at the same time providing thoroughly serviceable units of attractive appearance.

In an effort to reduce the over-all bulk and weight of both hand axes and hunting knives, the present inventor has devised a combined tool which efficiently satisfies the purposes of both a hand ax and a hunting knife while effecting a considerable saving in the overall weight and bulk of these articles. Since these tools must be carried over long distances and over difficult terrain, the advantage of having tools that are light while also being rugged and thoroughly capable of serving their intended purposes is readily obvious.

Accordingly, the primary object of the present invention is to reduce the over-all bulk and weight of hunting knives and hand axes by providing a combination tool which effectively satisfies the purpose of both a hunting knife and a hand ax.

A further object of this invention is to provide a combination tool and instrument having separate ax and knife blade members which may be selectively engaged with and secured to a single handle.

Another object of this invention is to provide an ax head and a knife blade having similarly shaped shanks or tangs which are selectively engageable in slots provided in a single handle member.

A still further object is to provide novel means for selectively locking either an ax head or a cutting blade in a single handle member.

Another object of this invention is to provide a carrying case adapted to enclose and support the combination tool of this invention and further to provide novel forms of construction for knife blades, ax heads and cooperative handle members therefor.

Further objects and advantages of the present invention will be apparent from the appended description and drawings in which:

Fig. 1 is a perspective view showing the general arrangement of the elements of this invention together with a carrying case;

Fig. 2 is a perspective view of a knife blade and cooperative knife handle in disassembled relation;

Fig. 3 is an elevation in partial section showing further features of the handle member of this invention;

Fig. 4 is an elevation showing the features of an ax head blade member formed in accordance with this invention;

Fig. 5 is a top plan view of the ax head of Fig. 4; and

Fig. 6 is an elevation in partial section showing the handle member and a blade member in cooperative locked position.

Briefly stated the present invention provides a combination tool which may be conveniently carried as a unit in a carrying case. The combined tool and case are of

2

light weight and accordingly readily adapted to use during participation in outdoor sports or activities. As a unit, the combined tool of this invention provides a single handle and separate knife and ax head blade members which are selectively and separately engageable with the handle.

In order to effect the interchangeable engagement of said knife or ax head blade members, the tang of the knife and a tang formed on a shank of the ax head are similarly formed to provide split tangs, one of which is further provided with a notch on its outwardly disposed surface. The divided tang members are adapted for sliding reception in cooperative slots formed in the handle member and a catch is provided on the handle for selective engagement in said notch to secure the knife or ax head blade members in the handle. As further features of this invention, angular surfaces on the tangs and on the handle are designed to force the notch and catch into secure engagement. Further a special built-up type of striking member is provided on the ax head which materially reduces the cost of fabrication while providing a suitable type of drive member for the accomplishment of various secondary tasks usually accomplished by ax heads. The carrying case of this invention further provides a compact and light weight unit which enhances the utility of this combination tool.

Referring now to the drawings, the details and features of this invention will be more fully explained. In Fig. 1, the combination tool of this invention is shown in its ax-carrying relation in a carrying case 11. The carrying case 11 is provided with a pocket 12 shaped for the reception of the ax head 13. A flap 14, shown in its open position, is provided to enclose the entire ax head 13 when the ax is moved downwardly into the pocket 12. A knife sheath 16 is attached to the carrying case 11 by means of rivets 17, stitching or the like. The sheath 16 provides a receptacle shaped to cooperatively engage the knife blade 18 which is introduced therein, and the single handle member 19 is further secured to the carrying case 11 by means of a strap 21 having cooperative snap fasteners on the ends thereof.

The exact structural shape of the knife blade 18 and handle member 19 is more clearly shown in Figs. 2, 3 and 6. In these figures it will be noted that the knife blade 18 is provided with an elongated and rounded cutting edge 23 which intersects the back edge 24 of the knife blade 18 to provide a point 26. Actually the knife blade 18 is of conventional shape.

In order to provide adequate support for the usual cutting operations, an elongated and divided tang 27 is formed unitarily with the knife blade 18. In a preferred form the tang 27 is split or bifurcated to form upper and lower tang members 28 and 29 respectively having a slot 31 therebetween. The outermost ends of the tangs 28 and 29 are similarly shaped to provide short rectangular extensions 32 and angular surfaces 33 and 34 adjacent thereto. The outer edge 36 of the lower tang 29 is provided with a notch 37 positioned intermediate the longitudinal extent of said tang.

The handle 19 is of conventional shape providing a grip portion 38, a bolster 39 and a guard 41. In the actual construction, the bolster is secured to a central frame portion 42 by means of rivets 43 or the like and the guard is secured to the frame 42 by forming a flange 45 on an extension of the frame 42. The grip portion 38 of the knife handle 19 is made up of separate grip pieces 44 of plastic, bone, laminates or other similar materials which are likewise riveted to the opposite faces of the frame 42 by means of other rivets 43. Preferably the frame 42 and the attached grip pieces 44 are cooperatively formed to provide a grip portion 38 which may be conveniently and comfortably held in the user's hand.

In Figs. 3 and 6 the actual construction of the frame 42 is more clearly shown. In these figures it will be noted that the frame 42 is provided with upper and lower slots 46 and 47 respectively of size and shape to cooperatively receive the tangs 28 and 29 respectively of the knife blade 18. Further a longitudinal wall 48 separating the slots 46 and 47 is of such shape and size as to be cooperatively received in the slot 31 between the tangs 28 and 29. Rectangular recesses 49 are pro-

vided at one end of the slots 46 and 47 for the cooperative reception of the extensions 32 and angularly disposed surfaces 51 and 52 are provided for engagement with the angular surfaces 33 and 34 on the knife blade 18. It is intended that when the tangs 28 and 29 of the knife blade 18 are inserted through openings 53 and 54 in the guard 41 and into the slots 46 and 47, the tangs 28 and 29 which are preferably of slightly divergent separation will be moved into aligned position when the angular surfaces 33 and 34 come into mating contact with the angular surfaces 51 and 52 of the frame 42. Since the knife blade 18 is made of relatively resilient material, the tangs 28 and 29 will, however, tend to return to their natural divergent positions. This spreading force, when exerted against the angular surfaces 51 and 52 tends to cause outward longitudinal movement of the tangs 28 and 29 with respect to the handle 19. This spring force and movement is utilized to provide means for securing the knife blade in its engaged position with respect to the handle 19.

In effecting such utilization, a catch 56 is pivotally mounted on the guard 41 by means of a pivot pin 57. In its disengaged position, the catch is disposed out of engagement with the knife blade 18 substantially as shown in Figs. 2 and 3. In its alternate engaged position adjacent to the handle 19, the catch 56 passes through the opening provided by the slot 47 and into engagement with the notch 37 on tank 29. When in this position the spreading tendency of the tangs 28 and 29 exerted against the angular surfaces 51 and 52 tends to move an inwardly disposed edge 58 of the notch 37 into engagement with the outermost edge 59 of the catch 56. This engagement between the notch 37 and catch 56, when acting together with the cooperative shaping of the tangs 28 and 29 and the notches 46 and 47, tends to hold the knife blade 18 in secure position with respect to the handle 19. Accordingly whenever it is desired to use the knife portion of this combination tool, the tangs 28 and 29 of the knife blade 18 are inserted in the slots 46 and 47 to force the angular surfaces 33, 34, 51 and 52 into engagement. Slight angular pressure exerted on the knife blade 18 causes further inward motion of the knife blade 18 so that the catch 56 may be engaged in the notch 37.

When it is desired to remove the knife blade 18 from the handle 19, a slight inward pressure is exerted on the knife blade 18 to cause relative motion between the angular surfaces 33, 34, 51 and 52 of sufficient magnitude so that the catch 56 may be moved out of engagement by gripping the grooves or serrations 61 on the catch 56.

When the knife blade 18 is removed from the handle 19, the handle may be used to grip bifurcated tangs 28 and 29 of an elongated shank 62 of the ax head 13. In manner similar to that previously described, the tangs 28 and 29 provide a slot 31, and extensions 32 of size and shape corresponding to the tangs, slot and extensions of the knife blade 18. Further angularly disposed surfaces 33' and 34' are provided for cooperative engagement with the angularly disposed surfaces 51 and 52 of the frame 42. Tang 29' is further provided with a notch 37' on its outwardly disposed edge having an edge 58' for engagement with the end 59 of the catch 56.

Further features of the ax head 13 are clearly shown in Figs. 4 and 5 where it will be noted that the ax head 13, the shank 62 and the tangs 28' and 29' are formed of a single thickness of material. A curved end 63 of

the ax head 13 is provided with bevel surfaces 64 to provide a blade or cutting surface at the edge 63. An opposite rounded edge 66 of the ax head 13 provides support for laminated sections 67 of material welded or otherwise bonded to the single thickness of material forming the ax head 13. This particular construction is utilized to form a striking surface 68 made up of the curved edge 66 and cooperative edges of the laminated sections 67. Besides providing such a striking surface 68 which may be utilized for driving nails or other similar purposes, the laminated sections 67 act as counterbalancing weights which tend to give the ax head 13 a better balance while also increasing the cutting efficiency of the edge 63.

Since only a single handle is provided for use with both types of cutting blades, it is readily apparent that the present combination tool materially reduces the weight of necessary equipment which must be carried by those engaged in outdoor activities. Further, since the form of construction here represented likewise saves considerable weight, it will be apparent that the present inventor has satisfied a first object of his invention. Likewise it will be apparent that the other objects of the invention have been fully satisfied by the devices shown. Further while only a single embodiment of this invention has been shown and described, it will be apparent to those skilled in the art that the device of this invention is adaptable to other modifications and changes. All such modifications and changes as are within the scope of the hereunto appended claim are deemed to be a part of this invention.

What is claimed is:

In an article of cutlery having a relatively resilient blade member with a cutting edge, a bifurcated shank connected to said blade member providing a pair of normally divergent tangs, one of said tangs having an elongated notch in an outwardly disposed edge thereof, said notch having a length approximately half the length of the tangs, said tangs having angularly disposed surfaces adjacent the ends thereof, a handle having slots therein for the reception of said tangs, said slots having internal angularly disposed surfaces for engaging the angularly disposed surfaces on said tangs and cooperating therewith for inwardly displacing the tangs when said surfaces are in intimate relation to positively align said tangs with said handle slots, an end pivoted elongated catch for selective engagement in said elongated notch, said catch recessing in said notch to form a portion of the grip of the handle and securely hold the handle to the blade, and exposed easily accessible gripping means for grippingly removing said catch to an alternate position out of engagement with said notch when it is desired to release and remove the blade member from the handle, said catch member being removable from said notch when the angularly disposed surfaces are engaged to displace the said tangs inwardly.
